UNITED STATES PATENT OFFICE.

GEORGE R. CORNWALL, OF RYE, NEW YORK, ASSIGNOR TO AMERICAN PLANOGRAPH COMPANY, A CORPORATION OF WEST VIRGINIA.

PRINTING-PRESS.

1,105,966.

Specification of Letters Patent.

Patented Aug. 4, 1914.

Application filed November 10, 1906, Serial No. 342,788. Renewed June 20, 1914. Serial No. 846,384.

To all whom it may concern:

Be it known that I, GEORGE R. CORNWALL, a citizen of the United States, residing at Rye, in the county of Westchester and State 5 of New York, have invented new and useful Improvements in Printing-Presses, of which the following is a specification.

The invention relates to rotary printing machines and more particularly to rotary 10 machines which print by an offset impression.

Objects of the invention are to provide a press for printing upon both sides of the impression-receiving material by an offset impression; to provide a press which shall be compact and convenient; to provide means for protecting the printing surfaces from injury by failure of the impression-receiving material, or otherwise; to provide means 20 for controlling the impression and the action of the inking mechanism both automatically and manually; to provide adjustments for the various parts of the mechanism; to provide a press which may be simply and expeditiously set to print either a single or perfecting impression. These and other objects of invention will in part be obvious and will in part more fully appear herein.

The invention consists in the novel part. 30 arrangements, improvements and combinations herein shown and described.

The accompanying drawings, referred to herein and forming a part hereof, illustrate one embodiment of the invention, the same 35 serving in connection with the description herein to explain the principles of the invention.

Of the drawings: Figure 1 is a side elevation of a printing press constructed in 40 part in accordance with the principles of the invention; Fig. 2 is an enlarged view of a part of Fig. 1; Fig. 3 is a longitudinal section, corresponding to Fig. 2, just within the front frame, and looking inwardly; Fig. 45 4 is a fragmentary sectional view of one of the form cylinders and its offset cylinder; Fig. 5 is a corresponding view of Fig. 4 with the parts in a different relation; Fig. 6 is an end elevation on the line A—B of Fig. 1 looking in the direction of the arrow; Fig. 7 is a detail of the clutch mechanism; Fig. 8 is a plan view, partly in section, upon the line C—D of Fig. 1; and Figs. 9 and 10 are views serving to show the general way

with relation of the cylinders to each other 55 in their various positions.

In the accompanying drawings which show by way of example one embodiment of the invention two form cylinders are shown and indicated by the reference numerals 1 and 2, and offset printing cylinders 3 and 4 are also shown. The form cylinders and offset printing cylinders are so constructed and arranged that each of the form cylinders imparts an inked design to one of the 60 offset cylinders, the offset cylinders being constructed and arranged to form a printing couple to perfect an impression-receiving material passing therebetween. In the illustrated embodiment the offset printing 70 cylinder 3 receives its inked design from the form cylinder 1 and the offset cylinder 4 receives its inked design from the form cylinder 2. According to certain principles of the invention, however, it is contemplated 75 that the press act as a single impression press, when desired, to print upon one side only of the impression-receiving material, and accordingly means for easily and expeditiously changing the press from a perfecting to a single impression and vice versa are included by the invention and a form of such means is herein shown and described.

The forms may, according to certain features of the invention, be of any kind but 85 according to certain features of the invention the use of planographic forms or printing plates is contemplated and such forms are shown in the present embodiment. Suitable inking devices are provided which may 90 be of any approved and convenient form so far as regards many aspects of the invention. In the illustrated embodiment each of the form cylinders is shown as having associated therewith an inking fountain 95 with which co-operates a vibrator 6, a system of distributing rolls 7, and a series of form rolls 8. The vibrator 6 receives suitable motion from a cam 9 acting upon a lever 10 which connects by a link 11 to a bell 100 crank lever 12 on which the vibrator 6 is mounted. The inking devices, so far as described, constitute known forms and need not be set forth in further detail.

With the planographic form cylinders 105 suitable damping mechanism is provided. According to certain features of the invention such damping mechanism may be of

any approved or convenient form. As shown herein such damping mechanism includes a water fountain 13, a fountain roller 14, a vibrating roll 15, and form damping 5 rolls 16. The vibrator 15 receives its movement from a cam 17 mounted upon a suitably driven shaft 18, the bell crank lever 19 upon which the vibrator roll is mounted being in operative relation to the said cam. A 10 spring 20 serves to hold the lever to the cam. The damping mechanism, in so far as described, is old and well known and need not be set forth in greater detail.

Suitable devices are provided for supplying 15 the impression-receiving material to be printed upon. In the illustrated embodiment said devices are designed for handling the impression-receiving material in the form of a web. A shaft 21 is shown supporting a paper roll 22. A pivoted bearing piece 23 for holding the shaft 21 in position is also provided, said piece being in turn secured by a latch 24. The web is then carried over a roll 25 up past the printing couple 20 25 and between feeding rolls 26 shown herein as being positively driven. The web may be received from the printing machine in any suitable manner as by a reeling device, or by a sheet-cutting device, or by a folding machine, or otherwise. As herein shown, the press is provided with a side delivery. To effect this there is shown above the feed rolls 26 a turning bar 27 about which the web turns and is delivered sidewise, as above 30 35 stated. While but a single turning bar is shown a plurality of such bars or other suitable devices may be employed if desired.

The various parts of the press are supported in suitable relation to each other by a 40 frame of any convenient shape, such frame being designated herein generally by the reference numeral 28. Any suitable form of driving means may be employed. In the form thereof herein illustrated a shaft 29 is 45 shown having mounted thereon a fast and loose pulley 30 and also a gear wheel 31. Suitable gear connections from the gear wheel 31 serve to drive the various parts of the press either directly or indirectly. As 50 such driving connections may be of any form found suitable or convenient for the purpose, they will not be described herein in detail.

According to certain aspects of the invention 55 it includes automatic means for throwing off the impression controlled by the impression-receiving material and according to certain features of the invention means are provided for manually throwing off the 60 impression. In certain aspects of the invention also, means are provided for moving the printing offset cylinders away from impression and at the same time moving them 65 out of contact with their respective form cylinders while preserving the angular rela-

tion of each offset printing cylinder to its form cylinder. The form of such means shown herein comprises a detector mechanism of convenient or suitable form constructed and arranged to co-act with the impression-receiving material so that the failure of the material, as by breaking, or through defects therein, or otherwise, will cause the detector mechanism to set in motion the devices for accomplishing the functions 70 75 just described.

In the illustrated form the detector mechanism is in circuit with a suitable source of electric energy, such as a battery 32, the failure of the impression-receiving material serving to cause the detector mechanism to close the circuit and thus set its associated mechanism into operation. Said mechanism comprises a series of rolls 33 over which the web of impression-receiving material travels. A 80 85 series of rolls 34 rest upon the web, the said rolls 34 being mounted in pivoted arms 35. The action of gravity or of a spring or other suitable device brings the rolls 33 and 34 into contact in case of breakage of the 90 web or of a torn or defective place therein.

In the illustrated embodiment the offset cylinders 3 and 4 are shown as having their shafts 36 and 37 journaled in eccentric bearings 38 and 39, said bearings being carried in pillow blocks 40 and 41. The said pillow blocks are shown mounted to slide vertically in bearing blocks 42, 43 which are in turn horizontally slidable upon suitable guides carried in the frame of the press. Adjusting screws 44 are provided for the bearing blocks in order that the "squeeze" between the printing cylinders may be regulated. The pillow blocks 40, 41 are also shown provided with adjusting means, the form thereof 105 shown herein comprising springs 45 having a screw adjustment 46 for regulating the tension thereof, the said springs serving to keep the offset cylinder yieldably in contact with its form cylinder. The said springs 45 serve also to keep the pillow blocks normally 110 to position against an adjustable stop 47. It will be understood that the form of adjustment for the contact pressure between the offset printing cylinders and between 115 each offset printing cylinder and its form cylinder may be of any form desired and that either the yielding adjustable devices may be used in both cases or the non-yielding adjustable devices in both cases, or in 120 any manner desired. The eccentric bearings are shown provided with crank arms 48 to which are connected pivoted links 49 which are in turn pivoted to sliding rods 50. The said rods 50 are normally held to position 125 by any suitable means such as the springs 51. The tension of these springs may be regulated by suitable devices such as the adjustable collars 52.

Connected to the sliding rods 50 there is 130

further shown in the present embodiment bell crank levers 53 fixed upon a rock shaft 54 carried in the frame of the machine. Fixed also upon the rock shaft 54 is an arm 55 in operative relation with a cam 56 carried upon a shaft 57. The said shaft 57 is mounted in a suitable manner as in bearings 58 and is normally in a state of rest. Sleeved for rotation upon said shaft is a gear wheel 59 carrying one member 60 of a cone clutch. The other member 61 of the cone clutch is carried fixed relatively to shaft 57. Suitably carried with reference to the shaft 57, and shown herein as carried upon the cam disk 56, are latch members 62 and 63. A bell crank lever 64 is mounted so as to co-act with the said latches, the free end of said bell crank lever bearing against a collar 65, the said collar being in operative relation to a spring 66, which tends to bring the clutch members 60 and 61 together. Each of the latches 62 and 63 are shaped so that when they engage the lever 64 they first rock it upon its pivot 25 and are then brought to rest against the lever. The latches 62 and 63 are pivotally mounted to rock upon their bearings and are normally spring-held to position. Mounted adjacent to the bell crank lever 64 and 30 so as to be in operative relation with the latch in engagement therewith is a trigger 67. Upon the other end of the said trigger there is shown herein an armature 68 in operative relation to a magnet 69 which is in 35 circuit with the detector devices, the form of detector devices herein shown being constructed and arranged for operating the throw-off mechanism electrically.

The detector devices may be of any suitable form, and the form herein shown comprises a row of disks 33 on one side of the web of impression-receiving material and a row of disks 34 on the other side thereof. These disks are in circuit with the magnet 69 and a suitable source of electrical energy such as the battery 32 and by reason of the failure of the impression-receiving material, or upon the occurrence of a defect therein, the disks then move together to close the 40 circuit and to call the throw-off mechanism into action. In the present form the disks 34 are mounted upon arms 35 which may be permitted to drop by gravity, or may move by spring impulsion, or otherwise, to close the 45 circuit. There is also shown attached to the trigger 67 a pivoted link 70 connected also to a foot lever 71. A suitable circuit-breaker may be provided in the circuit, a form of such device being shown in Figs. 4, 5 and 6 of the drawings. Said form comprises a disk 110 mounted on shaft 57 to rotate therewith. Said disk is of insulating material with a block 111 of conducting material carried therein. Normally the block 55 111 rests between contacts 112 but on ro-

tation of the shaft 57 it passes out of engagement with said contacts and breaks the circuit. By this arrangement the magnet 69 is deenergized and the trigger 67 returns to normal position. Thus the latch 63 will be 70 permitted to engage the lever 64 and stop the press in the throw-off position.

A form of belt shifting mechanism is shown herein comprising a belt shifter 72 having attached thereto a latch lever 73 75 and also a pivoted lever 74 connecting to a link 75 attached to a lever 76 in operative relation with a cam 77 carried upon the shaft 57. Means are also provided, according to certain features of the invention, for 80 throwing off the form inking rollers. It is further contemplated to provide means for throwing off said form inking rollers at the same time that the impression is thrown off and substantially simultaneously therewith, 85 or for throwing off one set of form inking rollers independently of the other mechanism so that the press may be run to print upon one side only if desired. The form of means for effecting these functions shown 90 herein comprises slides 78 in guides 80 mounted upon the press frame and constructed and arranged to move into engagement with the form inking rollers to throw them off or to move away permitting them 95 to return to position. Pivoted to the said slides 78 are toggle levers 81 which may be connected by a suitable link 82. To one of the said toggles a crank arm 83 is shown connected so as to make and break the toggle. Pivoted to the said crank arm 83 is a link 84 attached to a bell crank 85 which is in turn pivoted to a rod 86. The rod 86 is connected to a lever 87 shown herein in the form of a hand latch lever having a suitable quadrant 88. The connection between the rod 86 and the lever 87 is shown in the form of an angled slot 89. The lever 87 is connected by a link 90 to one of the bell 100 crank levers 53.

In the present embodiment the form of means for throwing off the ink from one of the form cylinders independently of the other mechanism is shown as applied to the left hand form cylinder, referring to Fig. 1 of the drawings. In the illustrated form of such means the link 84 is shown as having a pin and slot connection with its bell crank lever 85 so that while the rod may be moved independently of the bell crank 110 lever it will also move with the bell crank lever when the latter is actuated. Mounted upon the rod 84 is shown a collar or lug 91. Adjacent thereto is further shown a hand lever 92. The lever 92 has connected thereto a spring which serves to hold the lever from following the lug 91 when the inking devices are thrown off by the other mechanisms. Suitable devices are also provided for moving the damping rolls away 115 120 125 130

from the form cylinder and the form thereof shown in the illustrated embodiment comprises an arm 93 upon which the damping rolls 16 are mounted. A gear 94 concentric with the pivot point of the arm 93 serves to drive the said rolls through the gear train 95. Fixed with references to the arm 93 is an arm 96, the free end of which is normally held by a spring 98 against a lug 10 on arm 96 whose free end cooperates with a cam 97 fixed upon the shaft of the form cylinder 1. A spring 98 serves to yieldingly hold the arm 93 and the cam arm 96 in proper position so that the movement of the arm 96 by its cam will move the damping rolls on arm 93 toward and away from the form cylinder.

Mounted upon the arm 93 is a pin 99. Pivotedly mounted upon the frame of the machine there is shown a detent arm 100 which is impelled into the path of the pin 99 as the arm 93 vibrates backward and forward by suitable means, such as a spring 101, but is normally held out of such path by a spring latch 102 carried upon a lever 103 pivoted upon the frame of the machine. The lever 103 is connected by a link 104 with the lever 92. When the lever 92 is actuated to throw off the form ink rollers 30 from the form cylinder 1 the latch 102 with its lever 103 is swung downwardly permitting the detent 100 to move forward so that as the arm 93 is vibrated the detent taking over the pin 99, will hold the form damping rolls away from the form while the inking rolls are also held cut.

Means for throwing off the feed of the impression-receiving material is also contemplated by the invention and in the illustrated form thereof the feed rolls 26 are shown mounted upon arms 105 fixed upon the shafts 106. Fixed also upon the said shafts are crank arms 107 connected by pivoted links 108 to a collar loosely encircling the sliding rod 50. It will thus be seen that as the rod 50 slides to move the offset printing cylinders away from impression that the rolls 26 will also be moved out of contact with the impression-receiving material by means of suitable stops, shown herein in the form of a nut 200 and lock nut, mounted upon the rod 50.

The operation of the herein-described mechanism is substantially as follows: While the press is running in case the detector mechanism is called into operation by failure of or defect in the web, the electrical circuit will be closed and the magnet 69 become energized. The magnet will thereupon attract its armature 68 and the trigger 67 will serve to trip the latch 62. Thereupon the spring 66 will move the collar 65 rocking before it the crank 64. The collar 65 draws with it the member 61 of the cone clutch until it engages with the member 60

carried by the rotating gear wheel 59. The shaft 57 then begins rotating and the cam 56 acting through the arm 55 and shaft 54 oscillates the bell crank levers 53 to draw the sliding rods 50 downward against its springs 51. This serves through the links 49 and crank arms 48 to rotate the eccentric bearings 38 and 39 to move the offset printing cylinders away from the impression and out of contact with their form cylinders, as shown in Figs. 9 and 10 of the drawings. Such movement, however, does not separate the cylinders sufficiently to carry their gear wheels out of mesh with each other and thus the angular relation of the offset cylinders to their form cylinders is preserved. The action of the sliding rods 50 has also served through the links 108 and crank arms 107 and 105 to move the feeding rolls 26 out of contact with the impression-receiving material and thus stop the feed. At substantially the same time that the preceding operations occur the cam 77, acting through the lever 76, link 75 and lever 74, serves to shift the belt from the fast to the loose pulley, the latch lever 73 moving with the belt shifter and serving to hold it on the loose pulley until disengaged by hand. The high part of the cam 77 however passes from under the lever 76 so as to offer no obstruction to the shifting of the belt back to the fast pulley manually by means of the lever 73. As the cam 56 rotated the latch 63 has contacted with the bell crank lever 64, serving first to cam it so as to move the collar 65 and the member 61 of the clutch out of engagement with the member 60. The bell crank lever 64 in turn serves as a stop for the latch 63. The mechanism is thus brought to rest substantially in the position shown in Fig. 5, the printing cylinders being held out of impression and the feed rolls away from the impression-receiving material. The trigger 67 has also been restored to its normal position by the latch 63. When so desired the inking mechanism is also tripped with the impression. This action occurs through sliding rod 50, rocking bell crank lever 53, which moves the link 90 and lever 87 to actuate the rod 86 and thereby to rock the bell crank levers 85 to actuate the toggles 81 and to lift the inking rolls away from the form cylinder. In case it is desired to restore the ink before the printing cylinders are brought back to impression or in case it is not desired to throw off the ink with the other mechanism, the foot lever 109 may be positioned so as to hold the pin of the lever 87 in the straight part of the slot 89. It will also be understood that the impression alone or the impression and the ink may be tripped by the hand lever 87 if desired. When it is desired to throw off the ink and the water from one of the form cylinders so as to run the press for printing

one side only, the lever 92, as shown in the drawings, is depressed and by means of the lug or collar 91 carries down its rod 84 and through the toggles 81 moves the carriage 78 thus carrying the form rolls away from the form cylinder. At the same time the rod 104 swings the latch lever 103 downwardly and the detent 100 released from its latch 102 moves forward to engage the pin 99 and thus to hold the arm 93 with its form damping rolls away from the form cylinder. When the lever 92 is released the form inking rolls come back upon the form and the detent 100 is again moved out of the path of the pin 99. When it is desired to bring the printing cylinders back to the impression this may be done by means of the foot lever 71 which serves to actuate the trigger 67 and to trip the latch 62. The belt is then shifted by means of the hand lever 73 and through the clutch 60, 61 the shaft 57 is rotated until the cam 56 returns substantially to the position shown in Fig. 4 when the cylinders are again in impression. The latch 62 now serves to throw the clutch 60, 61 out of engagement again in the manner substantially as described above.

From all the foregoing it will be understood that a machine has been provided which realizes the objects of invention and advantages herein set forth, together with other objects and advantages.

The invention, in its broader aspects, is not limited to the particular constructions shown, nor to any particular constructions by which it has been or may be carried into effect, as many changes may be made in the construction without departing from the main principles of the invention and without sacrificing its chief advantages.

What I do claim as my invention and desire to secure by Letters Patent is:

1. A printing press including in combination a form cylinder, an offset cylinder receiving inked impressions from said form cylinder, inking mechanism for said form cylinder, a third cylinder constituting with said offset cylinder a printing couple, and means for causing the impression-receiving material passing to be printed upon by said offset cylinder, and automatic means controlled by said impression-receiving material for causing the offset and form cylinders to separate and for throwing off the inking mechanism from said form cylinder.

2. A printing press including in combination a form cylinder, an offset cylinder, said parts being so constructed and arranged that the offset cylinder will receive inked impressions from the form cylinder, a cylinder constituting with said offset cylinder a printing couple, said cylinders being constructed and arranged so that the offset cylinder is in impression contact with said form cylinder and with said third cylinder during the printing

upon the impression receiving material, inking mechanism for said form cylinder, and automatic means for moving the offset cylinder out of contact with its form cylinder and for simultaneously throwing off the inking mechanism from the form cylinder.

3. A printing press including in combination a form cylinder, an offset cylinder so constructed and arranged that the offset cylinder will receive inked impressions from the form cylinder, a cylinder constituting with said offset cylinder a printing couple, said cylinders being constructed and arranged so that the offset cylinder is in impression contact with said form cylinder and with said third cylinder during the printing upon the impression receiving material, inking mechanism for said form cylinder, and automatic means for moving the offset cylinder out of contact with its form cylinder and for simultaneously throwing off the inking mechanism from the form cylinder, the said parts being so constructed and arranged that the angular relation of the form cylinder and offset cylinder will be preserved as they move to and from contact.

4. A printing press including in combination a form cylinder, an offset cylinder, a cylinder arranged to form with the offset cylinder a printing couple, inking mechanism for the form cylinder, and means controlled by the impression-receiving material for moving the offset cylinder away from its form cylinder and for simultaneously throwing the inking mechanism off from the form cylinder.

5. A printing press including in combination two form cylinders, two offset cylinders, one offset cylinder receiving its design from one of said form cylinders and the other offset cylinder receiving its design from the other offset cylinder, said offset cylinders being arranged to perfect an impression-receiving material passing therebetween, inking mechanism for each of said form cylinders, means for throwing off the inking mechanism from both form cylinders, and means which may be set to hold the inking mechanism for one form cylinder out of action while the inking mechanism for the other form cylinder is in action so that the press may print upon one side only of the impression-receiving material, means for regulating the squeeze between said offset cylinders, and automatic impression tripping means controlled by the impression receiving material.

6. A printing press including in combination two planographic form cylinders, an offset cylinder for each of said form cylinders, said offset cylinders being constructed and arranged to perfect an impression-receiving material passing through the press, inking mechanism for each of said form cylinders, damping mechanism for said planographic

form cylinders, and means which may be set to hold the inking mechanism and damping mechanism for one form cylinder out of action so that the press may print upon one side only of the impression-receiving material.

7. A printing press including in combination a form cylinder, an offset cylinder, said parts being so constructed and arranged that 10 the offset cylinder will receive inked impressions from the form cylinder, inking mechanism for said form cylinder, a member co-acting with said offset cylinder to form a printing couple, said form cylinder, offset 15 cylinder and said member being constructed and arranged so that the offset cylinder may be in impression contact with the form cylinder and with said member at the same time, and means for throwing off the impression 20 and for throwing off the inking mechanism from the form cylinder.

8. A printing press including in combination a form cylinder, an offset cylinder, said parts being so constructed and arranged that 25 the offset cylinder will receive inked impressions from the form cylinder, inking mechanism for said form cylinder, a member co-acting with said offset cylinder to form a printing couple, said form cylinder, offset 30 cylinder and said member being constructed and arranged so that the offset cylinder may be in impression contact with the form cylinder and with said member at the same time, and automatic means for throwing off the 35 impression and for throwing off the inking mechanism from the form cylinder.

9. A printing press including in combination a form cylinder, an offset cylinder, said parts being so constructed and arranged that 40 the offset cylinder will receive inked impressions from the form cylinder, inking mechanism for said form cylinder, a member co-acting with said offset cylinder to form a printing couple, and means controlled by the 45 impression-receiving material for throwing off the impression and for throwing off the inking mechanism from the form cylinder.

10. A printing press including in combination a form cylinder, an offset cylinder, a 50 member arranged to form with the offset cylinder a printing couple, inking mechanism for the form cylinder, feeding mechanism for the impression-receiving material, and mechanisms controlled by the impression-receiving material for throwing off the 55 impression and also for throwing off the inking mechanism from the form cylinder, and for stopping the feed of the impression-receiving material.

60 11. A printing press including in combination a form cylinder, an offset cylinder, a cylinder arranged to form with the offset cylinder a printing couple, means for feeding an impression-receiving material between the offset cylinder and its impression 65

cylinder, and means controlled by the impression-receiving material for stopping the feed of the impression-receiving material, for moving the offset cylinder and form cylinder out of contact, and for throwing off the inking mechanism from the form cylinder.

12. A printing press including in combination two form cylinders and two offset cylinders, the said parts being constructed and arranged so that each of said form cylinders imparts an inked design to one of the offset cylinders and so that said offset cylinders form a printing couple to perfect an impression-receiving material passing therebetween, inking mechanism for each of said form cylinders, means for feeding the impression-receiving material, automatic means controlled by the impression-receiving material for throwing off the inking mechanism from a form cylinder, and means which may be set to hold said inking mechanism away from its form cylinder.

13. A printing press including in combination two form cylinders and two offset cylinders, the said parts being constructed and arranged so that each of said form cylinders imparts an inked design to one of the offset cylinders and so that said offset cylinders form a printing couple to perfect an impression-receiving material passing therebetween, inking mechanism for each of said form cylinders, automatic means for tripping the impression, automatic means for throwing off the inking mechanism from the form cylinders, and means which may be set to hold one of said inking mechanisms away from its form cylinder when desired.

14. A printing press including in combination two offset cylinders constituting a printing couple and between which the impression-receiving material is printed, two form cylinders, one imparting inked designs to one of said offset cylinders, and the other form cylinder imparting inked designs to the other offset cylinder, two inking mechanisms, one for each of said form cylinders, means controlled by the impression-receiving material for throwing off said inking mechanisms from their respective form cylinders, and means which may be set for holding one of said inking mechanisms away from its form cylinder while leaving the other inking mechanism under the control of said impression-receiving material.

15. A printing press including in combination two offset cylinders constituting a printing couple and between which the impression-receiving material is printed, two form cylinders, one imparting inked designs to one of said offset cylinders, and the other form cylinder imparting inked designs to the other offset cylinder, two inking mechanisms, one for each of said form cylinders, means controlled by the impression-receiving material

- ing material for throwing off the impression between the offset cylinders and also for throwing off the inking mechanisms from their respective form cylinders, and 5 means for holding one of said inking mechanisms away from its form cylinder, while leaving the other inking mechanism and the impression throw off under the control of the impression-receiving material.
10. 16. A printing press including in combination two form cylinders and two offset cylinders, the said parts being constructed and arranged so that each of said form cylinders imparts an inked design to one of the 15 offset cylinders and so that said offset cylinders form a printing couple to perfect an impression-receiving material passing therebetween, and means acting to move the said offset cylinders simultaneously away from 20 impression while maintaining each offset cylinder and its form cylinder in the same angular relation to each other.
17. A printing press including in combination two form cylinders and two offset 25 cylinders, the said parts being constructed and arranged so that each of said form cylinders imparts an inked design to one of the offset cylinders and so that said offset cylinders form a printing couple to perfect an 30 impression-receiving material passing therebetween, and automatic means for moving said offset cylinders away from impression and also out of contact with their form cylinders.
35. 18. A printing press including in combination two form cylinders and two offset cylinders, the said parts being constructed and arranged so that each of said form cylinders imparts an inked design to one of the 40 offset cylinders and so that said offset cylinders form a printing couple to perfect an impression-receiving material passing therebetween, and manually-actuated means for simultaneously moving said offset cylinders 45 away from impression and also out of contact with their form cylinders.
19. A printing press including in combination two form cylinders and two offset cylinders, the said parts being constructed 50 and arranged so that each of said form cylinders imparts an inked design to one of the offset cylinders and so that said offset cylinders form a printing couple to perfect an impression-receiving material passing there- 55 between, and automatic means for moving said offset cylinders away from impression and also out of contact with their form cylinders while still maintaining the angular 60 relation of the offset cylinders and their respective form cylinders.
20. A printing press including in combination two form cylinders and two offset cylinders, the said parts being constructed and arranged so that each of said form cyl- 65 inders imparts an inked design to one of the offset cylinders and so that said offset cylinders form a printing couple to perfect an impression-receiving material passing therebetween, and means controlled by the impression-receiving material for moving 70 said offset cylinders away from impression and also out of contact with their form cylinders while still maintaining the angular relation of the offset cylinders and their respective form cylinders. 75
21. A printing press including in combination two form cylinders and two offset cylinders, the said parts being constructed and arranged so that each of said form cylinders imparts an inked design to one of the 80 offset cylinders and so that said offset cylinders form a printing couple to perfect an impression-receiving material passing therebetween, and means for moving the said cylinders away from impression and 85 also out of contact with their respective form cylinders, said means being constructed and arranged to be controlled by the impression-receiving material or to be manually actuated. 90
22. A printing press including in combination two form cylinders, two offset cylinders, one of said offset cylinders and one of said form cylinders being geared to rotate together, said offset cylinders being constructed and arranged to form a printing couple, and means for simultaneously moving an offset cylinder away from impression and also out of contact with its form cylinder while maintaining the gears upon the 100 offset cylinder and its form cylinder in mesh. 105
23. A printing press including in combination two form cylinders, two offset cylinders, one of said offset cylinders and one of said form cylinders being geared to rotate together, said offset cylinders being constructed and arranged to form a printing couple, and means for moving an offset cylinder away from impression and also out of contact with its form cylinder while main- 110 taining the gears upon the offset cylinder and its form cylinder in mesh, said means being constructed and arranged to be automatically controlled or manually actuated. 115
24. A printing press including in combination two form cylinders and two offset cylinders, the said parts being constructed and arranged so that each of said form cylinders imparts an inked design to one of the offset cylinders and so that said offset 120 cylinders form a printing couple to perfect an impression-receiving material passing therebetween, means for feeding an impression-receiving material, and means controlled by the impression-receiving material 125 for moving the offset cylinders away from impression and for controlling the feed of the impression-receiving material.

25. A printing press including in combination two form cylinders and two offset cylinders, the said parts being constructed and arranged so that each of said form cylinders imparts an inked design to one of the offset cylinders and so that said offset cylinders form a printing couple to perfect an impression-receiving material passing therebetween, means for feeding an impression-receiving material, means for moving an offset cylinder away from impression and out of contact with its form cylinder, and means for controlling the said feeding means for the impression-receiving material.
- 15 26. A printing press including in combination two form cylinders and two offset cylinders, said parts being constructed and arranged so that each of said form cylinders imparts an inked design to one of the offset cylinders, the offset cylinders forming a printing couple to perfect an impression-receiving material passing therebetween, and means controlled by the impression receiving material for simultaneously moving both 25 the offset cylinders away from impression.
27. A printing press including in combination an offset cylinder and a cylinder constituting therewith a printing couple between which the impression-receiving material is run to be printed upon by said offset cylinder, means for regulating the squeeze between said two cylinders, a form cylinder for imparting an inked design to said offset cylinder, yielding means for regulating the 30 squeeze between said form cylinder and said offset cylinder, and means for throwing off the impression without disturbing the setting of said squeeze regulating means.
28. A printing press including in combination a plurality of form cylinders, ink rolls for each form cylinder, two offset cylinders constructed and arranged to form a printing couple and so that one of said offset cylinders receives a design from one of 40 the form cylinders and the other offset cylinder receives a design from another form cylinder, and means which may be set to separate the offset cylinders and to also throw off the ink rolls from the form cylinders or to separate the offset cylinders only.
29. A printing press including in combination a plurality of form cylinders, ink rolls for each form cylinder, two offset cylinders constructed and arranged to form a set 45 cylinders receives a design from one of the form cylinders and the other offset cylinder receives a design from another form cylinder, and automatic means which may be set to 55 separate the offset cylinders and to also throw off the ink rolls from the form cylinders to separate the offset cylinders and to also throw off the ink rolls from the form cylinders.
30. A printing press including in combination a plurality of form cylinders, ink 65 rolls for each form cylinder, two offset cylinders constructed and arranged to form a printing couple and so that one of said offset cylinders receives a design from one of the form cylinders and the other offset cylinder receives a design from another form cylinder, means for feeding an impression-receiving material between the form cylinders, and means controlled by the impression-receiving material, which means may be set to automatically separate the offset cylinders and to also throw off the ink rolls from the form cylinders or to separate the offset cylinders only.
31. A printing press including in combination a form cylinder, inking rolls therefor, an offset cylinder constructed and arranged to receive a design from said form cylinder, a member constituting with the offset cylinder a printing couple, means for supplying an impression-receiving material to the said printing couple, and means controlled by the impression-receiving material for throwing off the impression and for throwing off the inking rolls from the form 85 cylinder.
32. A printing press including in combination a form cylinder, inking rolls therefor, an offset cylinder constructed and arranged to receive a design from said form cylinder, a member constituting with the offset cylinder a printing couple, and means which may be set to throw off the impression and to throw off the inking rolls from the form 95 cylinder or to throw off the impression only.
33. A printing press including in combination a form cylinder, inking rolls therefor, an offset cylinder constructed and arranged to receive a design from said form cylinder, a member constituting with the offset cylinder a printing couple, means for moving the inking rolls away from or into contact with the form cylinder, power-operated means for separating the members of the printing couple, and connections between said means and the inking rolls which may be set to control the inking rolls from the power-operated means or to permit the control of the inking rolls by hand.

115
In testimony whereof, I have signed my name to this specification, in the presence of two subscribing witnesses.

GEORGE R. CORNWALL.

Witnesses:

JOHN D. MORGAN
CLARA PHILLIPS.
